(57) **CLAIM**

The ornamental design for a holder for a digital data receiver, as shown and described.

DESCRIPTION

1.1 is a top perspective view of the holder for a digital data receiver, in accordance with our design;

1.2 is a top plan view thereof; and

1.3 is a bottom plan view thereof.

The broken lines shown are included for the purpose of illustrating portions of the holder for a digital data receiver that form no part of the claim.

1 Claim, 3 Drawing Sheets

UNITED STATES PATENT AND TRADEMARK OFFICE
CERTIFICATE OF CORRECTION

PATENT NO. : D922,063 S
APPLICATION NO. : 35/508584
DATED : June 15, 2021
INVENTOR(S) : Matthias Kirchner et al.

Page 1 of 1

It is certified that error appears in the above-identified patent and that said Letters Patent is hereby corrected as shown below:

On the Title Page

Item (72) Inventors should read:

Matthias Kirchner, Munich (DE);
Michael Kettner, Munich (DE)

Item (30) Foreign Application Priority Data should read:

June 03, 2019 (EUIPO) 006560199-0001
June 03, 2019 (EUIPO) 006560199-0003

Signed and Sealed this
Twenty-fifth Day of January, 2022

Drew Hirshfeld
